UNITED STATES PATENT OFFICE.

JACOB LEUKART AND WALTER W. OWEN, OF COLUMBUS, OHIO, ASSIGNEES
TO THE NEW COLUMBUS WATCH COMPANY, OF SAME PLACE.

WATCH-MOVEMENT BOX.

SPECIFICATION forming part of Letters Patent No. 552,534, dated January 7, 1896.

Application filed May 18, 1895. Serial No. 549,732. (No model.)

To all whom it may concern:

Be it known that we, JACOB LEUKART and WALTER W. OWEN, citizens of the United States, residing at Columbus, in the county of 5 Franklin and State of Ohio, have invented a certain new and useful Improvement in Display and Shipping Cases for Watch-Movements, of which the following is a specification.

Our invention relates to the improvement 10 of display and shipping boxes for watch-movements, and the objects of our invention are to provide an improved box or case of this class of superior construction and arrangement of parts; to so construct and arrange the 15 same as to provide for the proper support and retention of a watch-movement within the box; to prevent the marring or injurious marking of the watch-dial by the bearing of one of the case-sections thereon or by the rotation of one of said sections, and to produce 20 other improvements the details of construction of which will be more fully pointed out hereinafter. These objects we accomplish in the manner illustrated in the accompanying 25 drawings, in which—

Figure 1 represents a face view of our improved box, showing a watch-movement supported therein. Fig. 2 is a side elevation of the same. Fig. 3 is a similar side elevation 30 with the lid-section removed. Fig. 4 is a central transverse section of our improved box, showing a portion of a watch-movement supported therein, said view being enlarged for the purpose of more clearly illustrating the 35 invention, and Fig. 5 is a plan view of the box with the lid-section removed.

Similar letters refer to similar parts throughout the several views.

In carrying out our invention we employ a 40 cylindrical cup or casing *a*, preferably formed of a suitable metal, the lower side of said section consisting of a glass disk, as indicated at *a'*. The band or side wall of the box-section thus produced has formed therewith at desirable intervals upwardly-extending spring- 45 catch tongues *b*, the latter being formed integral with said box wall or band and having additional length imparted thereto by the production of vertical parallel cuts *c* formed in 50 said box-band. The upwardly-projecting portion of each of these spring-tongues is pro-

vided with an outward and thence inward and upward bend to form a clamping-hook, as indicated at *d*. Between the tongues *b* and at a distance from the latter the upper edge 55 of the box-section *a* is provided with inwardly-projecting flanges *e*, the inner edges of the latter being curved in parallel alignment with the box-section top. Through the vertical wall of the box-section *a* and adjacent to the 60 upper sides thereof is formed at a desirable point a small opening *f*.

g represents the cover-section which, as shown in the drawings, is of a substantially cap shape, this wall or band being of such circumference as to be adapted to fit snugly 65 over the wall or band of the section *a*. The upper side of the section *g* also consists of a glass disk. The downward movement of this cap or cover section is limited by contact of its lower edge with a circumferential shoulder or bead *g'* formed at the base of the section *a*. The cover or cap section is provided in its side wall with an opening *h* which corresponds in size with the opening *f* of the section *a* and which is so located as to admit of 70 its being made to register with said opening *f* by proper rotation of the lid-section.

In utilizing our invention, the watch-movement is inserted in the box-section *a* dial upward until the projecting edge of the pillar-plate *i* of said movement bears on the in-turned flanges *e* of the box. The cap or lid portion *g* is then placed in position over the wall of the box-section *a*, as indicated in the 85 drawings. This operation results in the inner wall-surface of the lid-section pressing the clamping extensions *d* of the tongues *b* inward over the edge of the dial *k*. By the spring action of the clamping projections of the 90 tongues *b* the watch-movement is held firmly in place against the supporting-flange *e*. It will be observed that the movement-supporting parts of our improved box are so arranged as to result in the suspension of the movement 95 between the glass end plates of the box-sections, thereby preventing any contact of either the upper or lower surface of the movement with said box-section. It will also be observed that the movement is so supported 100 within the box as to prevent the scraping or frictional contact of the dial-plate with either

of the box-sections, thereby insuring said dial against injury.

In case it is desired to wind the watch contained in the box without removing the movement from the latter, the lid-section may be rotated until the two openings *h* and *f* register with each other and a key or other suitable winding device may then be inserted through said openings.

10 Having now fully described our invention, what we claim, and desire to secure by Letters Patent, is—

15 1. In a watch movement displaying box the combination with the box section *a*, the latter having upwardly extending and inwardly turned spring tongues projecting at intervals therefrom, of a cap or cover section adapted to inclose said section *a* and impart an inward pressure on the clamping portions of said 20 tongues, substantially as and for the purpose specified.

2. In a watch movement display box the combination with the section *a* having the up-

wardly projecting and inwardly turned spring clamping tongues *b* and inturned edge flanges *e* arranged between said tongues, of a cover section *g* adapted to engage with said section *a* and impart an inward pressure to said clamping tongues, substantially as and for the purpose specified. 25

3. In a watch movement displaying box the combination with the section *a* having upwardly extending and outwardly and inwardly bent clamping tongues, inturned edge flanges *e* and a wall opening *f*, of a cap or 30 cover section *g* adapted to inclose the wall of said section *a* and an opening *h* in said section *g* adapted to be made to register with the opening *f*, substantially as and for the purpose specified.

JACOB LEUKART.
WALTER W. OWEN.

In presence of—

ALBERT KRUMM,
WM. REEL.
